METHOD AND CONTROL DEVICE FOR LUBRICATING SYSTEMS

Filed Jan. 17, 1921

UNITED STATES PATENT OFFICE.

FRANCIS E. BUXTON, OF INDIANAPOLIS, INDIANA.

METHOD AND CONTROL DEVICE FOR LUBRICATING SYSTEMS.

Application filed January 17, 1921. Serial No. 437,961.

This invention has to do with the art of automatic lubrication for shaft bearings, and power motors generally, and it is especially adapted to crank shafts and the crank arms operated thereby. In its preferred embodiment the invention as a method and system, comprises oil control devices,—such as means added to and coacting with, one or more main bearing sleeve elements, which first act to directly compress oil, and then sub-divide the same, in order to be used directly, as lubricant and indirectly, as means to cool; automatic discharge controlling devices, and exhaust delivery devices being the means that channel connect directly, separated bearing elements.

While the invention includes the combined instrumentalities above mentioned, I wish it to be understood that I consider the aforesaid means not only combinatively novel, but in so far as I am advised, the devices going to make up such means are new, aside from the said combinations that make for the whole, as will more clearly appear hereinafter.

To fully explain the advantages of my invention I shall refer briefly to the operation of other well known methods.

Lubrication means as heretofore arranged, even in the most carefully designed motors signally fails, since the said means does not prevent excessive heating within their bearings. And allowed to remain, as results indicate, said frictional heat rapidly expands in volume and tends to likewise expand the surface of the bearings, and thus practically closing the running clearance spaces therein.

Moreover, the ordinary method of center channeling the crank shafts of motors, or the like to facilitate lubrication, it not only adding a major expense, but such a tortuous path requires that the oil pressure be carried excessively high, which tends to break down its value. And further,—an obstruction may by blocking one of the small channels connecting each bearing in such an arrangement, not only stop the flow of oil to that one, but eventually to all, and thus, may seizing become general. And other causes which contribute toward this said effect are mentioned in classified order.

First, the ordinary brass backed bearing sleeve, having a high thermal resistance baffles very materially the escape of heat directly through the wall of the said member.

Second, the conventional bearing sleeve does not in service remain true in form, to correspond with that of the shaft which it should conform to and support. So to mention again, the ordinary method employs super-pressure, in order to force lubricant within a necessarily small, but in this instance, inaccurate clearance space.

Consequently, under the above mentioned conditions, the necessary oil-film breaks, and in ruptured sections the same is carried round and round within the bearing, and thereby seizing results.

Finally, the mechanical difficulties to be met, in order to properly retain this desired film—became so great, that balls and rolls have been inserted within bearings, to act as a substitute for oil.

With the foregoing in view, this invention provides a means to deliver, compress and dispense automatically, a continuous supply of oil for lubrication and the absorbing of heat, throughout the confines of a motor, or other like machines. Said pressure supply is so positioned, as to be channel connected directly, with the adjacent clearance spaces, or zones of the main pressure bearings.

The said delivery means therefore, is susceptible of limiting the volume of oil, entering the said clearance spaces, and tends to bypass the major portion of the said oil into concentric jacket chambers positioned beyond the contour of the clearance zones. And said portion of oil therein, acts as a circulatory flush.

In addition, said clearance zones in all the shaft bearings, which include those carried by the cranks, are susceptible of readjustment in order to vary the thickness of the oil-film therein, this is desired by reason of the varied consistency of the commercial oils to be used: and as a necessary guard, locking means is provided, to protect the same from unauthorized tampering, after the necessary adjustments have been made. And as before premised, special means, have been devised to directly connect the main shaft bearings, with their adjacent crank arm bearings, the same device being combined with other instrumentalities of this invention, all of which will be now described in detail on reference to the accompanying drawings in which:—

Figure 1 is a general view in side elevation

and broken section, of an ordinary explosive motor, having the invention applied thereto.

Figure 2 is an end elevation of the same showing in a staggered cross section, the oil delivery means and the pump-bearing, that also compresses and dispenses oil for lubrication.

Figure 3 is an enlarged broken section of a motor valve head mechanism, showing the uppermost means provided to dispense lubrication. Figure 4 is a central cross section of the pump-bearing mechanism, also showing the manner in which the same may be operated.

Figure 5 is a side elevation of the same devices, with certain parts broken away and shown in section.

Figure 6 is a broken portion in section, of an oil control device, being a detail showing a second operative position.

Figure 7 is also a detail showing an oil scavenger roll removed, and to demonstrate its adjustability of length.

Figures 8, 9 and 10 are enlarged broken portions of a compressible bearing sleeve element, shown in section and plan, in order to illustrate in detail an oil control valve in its open and closed positions.

Figure 11 is a portion of one of the motors supporting cradles showing an innermost view of the same and the oil inlet openings.

Figure 12 is an end elevation of the pump-bearing, as a unit and the lower part in cross section taken vertically through the center, and shows the oil control valves at the lowermost position closed.

Figure 13 is a side elevation of the same the lower portion view is also a central cross section, showing the oil delivery sleeve device more clearly and its adaptability otherwise.

Figures 14 and 15 are end and side elevations, of the bearing-sleeve cage, also as an oil control device and taken on central sections. Figures 16 and 17, are end and side elevations of a bearing sleeve of a somewhat modified form and shown separable at an angle, said angle being at right angles to the parting line of its removed cage (referring to Fig. 14).

Figures 18 and 19, are side elevations of the rotor oil delivery sleeve, the former shown as turned 90 degrees relative to that of the latter, to illustrate its detachably attached means of assemblage.

Figure 20 is an end elevation of a modified form and manner of direct connected power means to operate the oil-pump bearing, also the arrangement of a priming device connected therewith.

Figure 24 is a side elevation of the same partially shown in broken section; Fig. 21 is an enlarged portion of a crank arm in direct channel engagement with a broken section of the oil pump-bearing device. Figs. 22 and 23,

are front end and side elevations also, of a slightly modified form of the oil delivery sleeve and the same are preferred in this invention.

Similar reference characters indicate like parts throughout the several drawings. The arrows shown on certain parts indicate the direction of rotation, and the smaller arrows denote oil pressure, except in some instances where they indicate the direction of oil circulation.

General construction.

The term "oil control", as used herein, is intended to include a rotor oil delivery element, or any equivalent device, that coacts toward, or functions in this improved system of lubrication. A very brief description of an ordinary explosive motor to which the attachment of this invention is applied will suffice, since the particular type of such a motor is immaterial to the invention which has a wide range of adaptability, to various kinds of motors or machines. Supplementing the above brief, and without referring to indices: Figs. 1 and 2, fairly represents one of such machines, the same embodying a main shaft carrying double crank arms, and in this instance, there are four. The shaft and the crank pins are in fact, not required to be hollow formed: for the reason which will be mentioned presently. To support and operate the said shaft, it is preferred first, to adjustably assemble the main bearings, which includes the special pump-bearing—one or more, also the crank operating bearings directly in their positions upon the shaft and the crank-pins, thus, comprising an operative unit. This said assemblage is then rotatably secured within suitable cradles, which are fixtures of the motor and carried by the same.

As before premised, the ordinary method however, with its complications and expense accruing from hollow channeling the shafts crank-pins and arms of said element, are, by this invention absolutely displaced. Since maximum lubrication is secured, by a profusion of radially positioned inlets that conduct pressure oil, from supply chambers positioned directly adjacent to the clearance zones of the bearings thereof.

The term "adjustable bearing-sleeve", as used herein, is intended to include any co-acting device directly attached thereto and should be considered a unit,—in this specification.

Therefore, referring to Figs. 15, 16 and 17, I show in detail, a modified form, of a previously constructed bearing element, and described by me in United States Patent No. 1,813,466.

Moreover, I use in my present construction, certain basic features of the above mentioned patent: particularly, the bearing-sleeve ele-

ment, but a modification as above premised. Therefore, it will be better to abridge the description relative to the old in combination.

5 *Pump-bearing devices.*

This device as a combination, comprises, a centermost bearing element which is formed in a manner to admit of reduction, relative to its inner diameter, by manual means exerted 10 through its supporting member, and this combined unit is rotatably carried by a cradle casing, which is a fixed part of any motor.

These three elements above mentioned, co-operate in such a manner as to provide a partial 15 vacuum, whereby oil is lifted, in this instance from the crank case reservoir and into a provided chamber, wherein the same is compressed, that the same may be forced throughout the confines of the system:

20 Referring to Figs. 12 and 13, I show the compressible sleeve element mounted within its oil delivery sleeve, but removed from the motor cradle. And in Figs. 14, 15, 16 and 17, are shown the several parts in detail. 25 The inner bearing in this instance, being in halves and indexed 2, 2', and means 4 to secure the same together. Whilst its outer form comprises reversed cones which converge near the center into a common diameter. Formed 30 in parallel and within the exterior of said sleeve, are series of spaced apart V-like grooves and positioned near the base of the same are series of angular indentations 8. And directly crossing said V grooves, are a 35 series of spaced apart however, transversely connected blanket-like oil spreading passages 50, 56' that connect up in a manner and for a purpose hereinafter premised. There being also annular reductions 9' formed near 40 the ends of the said sleeve.

An enveloping cage device 10, 10' which is also formed separable and comprising, a pair of suitable end collars 11, 11' that register within the said reductions carried 45 by the sleeve; and a plurality of bar portions 12, being integral parts of the cage and which normally fill the said V gaps of the said sleeve substantially. Positioned intermediate the ends of the said bars, are 50 radial openings 13, into which are mounted suitable valves 13' and in a manner to be automatically closed, by internal oil pressure, or, tend to open at a predetermined position, by differential oil pressures. It should 55 also be understood, that the diametric lines of separation of the above unit members is such, that their union concur at right angles, one with the other, thus adding an element of rigidity.

60 Surrounding the unit above described, and positioned slidably within the ends of the collars 11, 11' is a rotor sleeve, or oil-delivery member, comprising, two longitudinal sections 14, 15, the latter telescoping into the former a proper distance, by thread engage-

ment 14', said sections are also preferably formed in a manner to be separated through their diameters, and suitable screws as indicated, to secure the same together substantially. The inner form of said rotor sleeve 70 registers precisely with the periphery of the enclosed bearing unit, and when the former said sections are aligned thereto, this arrangement secures reversed conical contact of the several elements as desired. The exterior, of 75 this now complete rotor assemblage is in form cylindrical. However, its end portions 16, 17 are reduced, in order to slidably enter the heretofore mentioned cage collar's annular recesses. 80

There are formed on the periphery of said section 14, a series of equally spaced grooves 18 which occupy an intermediate longitudinal position, within the complete assemblage. A suitable packing means, (not shown in the 85 drawings) which may be formed of felt, or the like and inserted into the channel-gap circumferentially disposed at the outer junction of the said sections: The office of the said packing means, is to normally close the 90 ends of the channels, or pockets 18 as desired. There are provided near the ends and on the peripheries of said sections, series of radially projecting oil inlets 19 and the purpose of which will be presently mentioned. 95 And locking screw pins 19', 19'', the former being to fix permanently the rotative motion of the inner bearing unit with that of its main supporting section 14. And the latter, 100 is removably fixed in the adjusting section 15 for the purpose as stated. This concludes the description of the rotor sleeve and its assemblage.

105 *Oil delivery devices.*

In direct cooperation with the described rotor unit, is its supporting fixed cradle 20 having a chambered portion within and intermediate positioned. Said chamber 29 is divided longitudinally into two separate sections by bridge portions 30, 45 and thus made complete by the said rotor element positioned therein. The lowermost section of said chamber at its upper end, connects with an inlet oil passage 38, whereby oil is drawn 110 from a supply manifold 36. Within this chamber section oil is caused to accumulate at normal pressure, and has in this position no outlet other, than by the prearranged route of the filled channels 18 passing over 115 the said bridge 45, and directly into the adjacent compression chamber section. It should be understood, that the motion of the said rotor element is very greatly reduced, compared to the speed of the crank shaft 120 which the device supports, but is sufficient as arranged, to supply oil for the purpose desired.

125 The said compression chamber section has provided a plurality of outlets: the first to 130

mention being the exhaust passage 70, and from thence connectively into the cam shaft bearing group.

It is necessary here, to set forth in detail 5 the oil scavenger device, the same in fact is the operative element, that provides the necessary vacuum, which maintains the flow of oil into the said lower chamber. Positioned adjacently below the said exhaust passage, (referring to Fig. 6) is a suitable slot 10 40, having a securably attached closure 43, said slot is positioned directly over and in alignment with the inner rotor channels 18. And a roll portion 41 of such dimensions 15 as to slidably fit into the said slot, said roll when in its lowermost position fits into the said rotor channels and is thereby caused to roll, but in an opposite direction, as indicated by the arrow, and by this turning movement readily adjusts itself progressively to 20 the contour of the said supporting rotor. Said roll is also free to be deflected outwardly as desired, into the said slot.

And further, said roll is preferably formed 25 in sections in such a manner as to be automatically adjustable lengthwise, to guard against leakage. And means provided, whereby pressure oil is admitted by by-pass 47, which is for the purpose of balancing the 30 oil pressure exerted upon the said roll element and also tends to relieve the tension from the attached spring thereby. Now referring to the direct radial outlets from the 35 said compression chamber: as heretofore mentioned, oil inlets 19 are carried by the rotor unit. The same are opened automatically, and are in such a position to receive pressure oil only, at predetermined points uppermost in their rotation.

40 That portion of the pressure oil issuing from the said passages 19, (see Fig. 4) is directed into shallow distributing basins 49 positioned outwardly and parallel with the cage arms, as heretofore premised. And the 45 manner of dispensing oil from the said basins—as lubricant and otherwise, has been previously described. However, through these basins pressure oil is delivered to the acting valves.

50 *Exhaust oil delivery devices.*

Under the above head: Means to channel 55 direct the used lubricant that has issued from within the main bearings, is now in order. In Fig. 1, is shown an ordinary shaft 54 carrying a plurality of double cranks 28. There are also shown in this instance, three oil 60 pumping bearings supporting the said shaft. However, the above arrangement may be differentiated, by installing one, and in some instances, two plain oil circulating support bearings in place, of the first mentioned number of pumping units.

Said cranks have bearings therefor, and 65 the same are rod-connected with their pistons

in the ordinary manner. And as the channel connections of the several crank driving units are practically alike,—the rear pump-bearing and its adjacent crank connections, will be set forth.

To receive and dispose of the oil that has passed through the pump-bearing and convey it by a more direct and shortened path, into the said crank bearing: I prefer to provide annular collecting zones. Said zones are in fact, but ample clearance spaces, positioned just beyond the ends of the adjustable rotor element, that supports the main bearing. See Figure 5. Moreover, these zones are intimately connected by series of small 70 openings which are also connected with their adjacent charging groove 53, which in this instance, is required only in the front end of the main bearing. As its rear end portion carries special means 11³, 11⁴ for baffling 75 leakage substantially of all the exhaust portions are collected and seek an outlet through the channel means just described. (For clearness see Figs. 20, 21.)

80 In this preferred construction is shown the crank arm positioned in a manner to close the end of the said groove 53, said arm also carries an abutment or ledge K that extends into the said groove portion sufficient, to thus secure a substantial connection of the 85 two forward moving elements. Furthermore, there is provided within the arm portion an opening 57 which projects at an angle to the rotation of the said arm, and said opening is so positioned that it precisely registers with the said charging groove thereof. And positioned directly adjacent the opening 57 is arranged the uppermost section of a like receiving groove, which is carried by the crank bearing. This said groove is likewise formed by the moving arm into a closed channel 58 as desired. It should be evident that by this novel construction set forth, a continuous closed path for lubrication is provided, regardless of the relative rotatory positions of the two connected bearings, one with the other. And collectively, with the centrifugal sweep of the intermediate arm, and the angularity of the connective means 57 carried within the same, tends to increase the 90 mobility of the oil substantially.

95 There is a negligible coefficient of leakage present in the operation of the above described means, but this is desired, it being preferred in this manner, to baffle carbon and other grimy matter from entering the channels from without.

The means employed to direct oil from the receiving channel 58 positioned in the said plain bearing of the crank 28, is in fact, a replica of the means used in the main bearing unit, the same having been described, need not be repeated here, with this exception: that lubricant is percolated radially 100 into the clearance zone, by drawing the same 105

from, the receiving channel 58 positioned on the rear side of said bearing, and exhausts by like means that function on the front side thereof. And from thence channel connected 5 into an adjoining crank bearing by a suitable tube portion 65, secured to and carried by the said arm.

Furthermore, intermediate the ends of the 10 crank bearing unit, is provided an oil circulatory and cooling groove 58' which is formed into a channel, by its outer connecting rod assemblage 56. Said channel is connected with the said rod's wrist bushing of like form, by tube 59 and from thence, 15 through the hollow piston pin 61 which is connected with the clearance chamber 67 carried by the piston substantially.

It is preferred that the several crank bearing units, be free to turn and adjust themselves, within their rod mountings, by the 20 action of differential pressures exerted thereon in service, as the circumferential shifting of the same tends to preserve their clearance zones, which contributes toward their maximum lubrication.

Auxiliary channel devices.

Channel means has already been outlined, as leading into the hollow cam shaft. Now 30 to follow up in brief, the means used in this system, to proportion the volume of lubricant required, in the two differential valve mountings. (Again referring to Figs. 1, 2 and 3.) Provided, a lead pipe 71 vertically positioned, that channel connects with the intermediate cam-shaft bearing 66 and also with an uppermost horizontally extending pipe portion 72, which is carried by the valve 35 mountings 73. Said pipe having pairs of 40 downwardly spaced apart nipples provided thereon. Positioned directly under the said pairs of oil directing nipples, are pivot arms 74 which are carried by the cylinder-head. Said arms are provided uppermost with 45 partitioned drip-cups 75 and each partitioned portion having therein oppositely disposed oil conveying channels 75', and 75''. Said partitions are so staged under the said nipples, that a lesser portion of the lubricant is 50 delivered to the intake valve group as desired. As the former mentioned channel connects with the intake valve rods 76, 76 and the latter with the exhaust valve rods 77, 77 respectively. Also means carried by the said several rods, which convey lubricant to their 55 supports and valve seats. And suitable casings 78 that confine the returning residue of oil to the parts to be lubricated substantially. Also means 79 being direct connected with the 60 oil compression chamber, and attached at the uppermost end of the same a suitable sight pressure gauge 80, as indicated.

Power-operating devices.

65 One method, whereby I have devised to op-

erate the rotor-pump mechanism, consists of a line of reduction gears, (see Figs 4, 5) which connect with the driven spur-gear carried by the said mechanism, and a worm-gear mounted on the cam shaft, as indicated. Not electing to use the above means, further explanation of such, is unnecessary.

As I prefer to use, as heretofore premised: a modified form of drive, (referring to Figs. 20, 24) wherein is shown in broken sections 70 the said modification. And in order to show more clearly certain elements that are altered, I have designated such, by letters. However, the same bearing units are used in the latter, with this exception: the driven gear A, is 75 positioned at the foremost end of the rotor element, and the same is integral therewith which relieves the bearing unit collar 11, as shown.

The cradle portion C and its removable cap C', and within the said cap's flanged portion is provided a round opening D that extends vertically upward a suitable distance. And within the adjacent flange portion carried by the said cradle, is a like opening D', and intermediate the two said openings, is provided a concentric recess E, which is in fact, a clearance slot that connects with the interior of the casing or cradle. There is also provided a lug portion E' carried by the motor wall C², 90 the same being positioned vertically above and at a suitable distance from the said openings.

Said lug also carries a bushing F. Mounted within the said bushing, and the described lowermost bearing opening, is a rotatable rod G. And near the end of said rod is secured a driving worm-gear G² which substantially engages the said gear carried by the rotor element mounted within the said cradle. Secured to said rod and located directly under the said uppermost bushing, a driven worm gear G' which engages a like gear H' which is carried by the cam shaft H, the same being a part of the motor thereof. This above description covers the several duplicate devices, but the same are not shown in the preferred drawing.

Prior to the concluding, general operation of system, I will here describe in brief, the means used to conduct supply oil from the reservoir, to the several operative units:

There are various means that may be used in connection with this system for priming the same, but the following is preferred—

Positioned within the oil-screen 35 is an ordinary priming pump J which is power connected by an extension rod I, to the drive rod G as shown. Channel pipe J² which connects the said priming pump with a suitable pipe manifold 36. And minor connections 37 carried by the said manifold and so positioned as to directly connect the several oil-pump bearings thereto. Also a relief valve 39 mounted on the manifold pipe, and for the purpose of 120

relieving excess oil pressure therein when required.

Suitable means for the automatic release of said priming means, is not shown in the drawings.

General operation of system.

In this description, such terms are used which include the several alike mechanisms as 10 contributing toward operative action.

Bearing in mind that adjacent to the main shaft points of support, there are power actuating rods G which are adapted to engage and actuate the oil delivery mechanisms which 15 first deliver maximum lubrication within their own confines, and then urges the residue oil throughout the confines of the motor. The operation of the entire system will be clearly understood on reference to the following description.

Assuming that the preferred parts are in the full line positions as shown in Fig. 1 and in detail, Fig. 4, with the lowermost section of chambers 29; the same having been oil 25 filled by primer J. And by automatic action of suitable controlling means will cause oil to be elevated from the same chambers, by channels 18, which discharge their contents progressively, into the uppermost section of the 30 said chambers, wherein the said oil is compressed: By reason that the incoming volume of oil is greater, than is the outer restricted exhaust means 70 as provided.

And by reason of the advantageous position 35 of the bearing sleeve units, being fixed within and rotatable with their control member 14, 15,—so that: This provision affords, a two-fold operative disposition of the pressure oil. First, the radial inlet passages 19 carried by 40 the latter mentioned member open only, at predetermined points uppermost, in its rotating path, and through the same, oil is caused to directly enter distributing clearance spaces 49, and from thence through valve openings 45 13 into the main clearance zones.

It should now be obvious, that as the rotative members are carried downwardly, the said valve openings carried thereby having been normally open, have also closure elements 13' that are caused to close said openings. As the effective pressures within the 50 said clearances at this point are greater than is that of the oil pressure without the reinforcement of the lubricating film in this manner of operation is continuous.

Second, as the clearance zones wherein lubricant progressively enters, is of a necessity small: The major volume of the circulating oil, for this reason is caused to by-pass and 60 further urged into circulatory blanket-like channels 50, which are positioned directly adjacent the said clearance zones thereof.

And in cooperation further: Simultaneous with the closing of the aforesaid bearing 65 valves, are also the automatic closing of the

said radial inlets, which overrun provided bridge portions in the paths of their downward orbits. This concluding means acts as safety stops, to prevent the premature escape of the oil.

Owing to the provision of the operative channels thus acting as bafflers, to prevent a too hasty discharge; it should now be clear that the aggregates in the separate functions are compulsorily retained for a period until lapse of a required time for effecting proper reunion before reaching the exhaust.

Therefore, the used oil having reached the exhaust delivery channels 53 which are positioned at the extreme ends of all the bearings, 80 and from thence is the oil urged outwardly through rotatory connective means 57, that so connect the several series of crank bearings. Then said oil is urged upwardly through means carried by the connecting rods, and 85 thence into the pistons and the cylinder walls thereof.

It should be here mentioned, that the several pump bearing units contribute collectively, in maintaining oil on the crank shaft portions, at a constant pressure. And as a means of outlet, one or more conveying pipes 70, connect the lower system, with the secondary part, being the cam shaft bearings which are lubricated in the ordinary manner. But connected with the centermost chamber of the same, is a vertically positioned pipe 71, the same being connected at its uppermost end with means that deliver oil and sub-divide to each respective valve mechanism. So that, a minor volume only, is delivered into the receiving rods and valves, whilst the major volume is caused to flow downwardly by gravity, thus lubricating the exhaust valve elements. And further, said residue is directed 105 by suitable tubes 78 which are so situated as to assist in the lubrication of the lowermost moving parts of the same.

Having thus described the invention, what I claim as new is:

1. A mechanism of the class described comprising a fixed cradle, a bearing element located therein, a crank shaft passing thru and rotatably supported by the said bearing element, said bearing element comprising a 115 rotatable bushing and being provided with a plurality of pockets on its periphery, means for rotating said bearing element, a source of pressure, an inlet opening in the cradle connected to the source and adapted to intermittently communicate with the pockets in their rotation and to deliver oil thereto, outlets from said pockets to the bore of the bushing to supply oil to the crank shaft bearing, and a discharge outlet at a point circumferentially spaced from the said inlet and adapted to intermittently register with said pockets in their rotation, whereby the supply of oil in said pockets will be discharged and renewed upon each rotation of the bearing element. 120 125 130

2. A mechanism of the class described comprising a fixed cradle, a bearing element located therein, a crank shaft passing thru and rotatably supported by the said bearing element, said bearing element comprising a rotatable bushing carried within a rotor supporting member and being provided with a plurality of spaced apart pockets on its periphery, means for rotating said bearing element, a source of pressure, an inlet opening in the cradle connected to the source and adapted to intermittently communicate with the pockets in their rotation and deliver oil thereto, means carried by the cradle that 10 act with the said rotor member to force supply oil from the adjacent pockets and then thru suitable outlets to the bore of the bushing to supply pressure oil to the crank shaft bearing, and means carried within said outlets that cause them to act inversely at a point diametrically spaced from said inlet, to discharge the used lubricant outwardly and into provided drain channels and again at a predetermined point in their rotation adapted 20 to intermittently register with the pockets, whereby the supply of pressure oil will be renewed and discharged from within the bore of the bearing upon each rotation of the bearing element.
3. A mechanism of the class described comprising a fixed cradle, a bearing element located therein, a crank shaft passing thru and rotatably supported by the said bearing element, said bearing element comprising a rotatable bushing, said bushing having an outer form the extreme ends of which converge toward its center, and there being an enveloping cage member that registers within the periphery of the bushing, and a rotor delivery member that supports the bushing and interlocks within the end portions of said cage, the several members coacting to direct, compress and maintain oil within the bushing, pockets carried on the periphery of said rotor, means for rotating the unit bearing element, a source of pressure, an inlet opening in the cradle there being an oil supply zone connected therewith and adapted to communicate with said pockets and deliver oil thereto, an uppermost compression zone connected with the pockets, but spaced apart from the aforesaid zone to receive the oil, and means carried by the cradle that delivers oil from out the pockets, providing a vacuum, and means carried by said cage member, whereby pressure oil within said zone is directly delivered to the bore of the bushing and at a lowermost position, said means acting to retain the oil, but at a predetermined point of their rotation tending to discharge the used lubricant into a series of drain channels spaced without, upon each rotation of the bearing element.
4. A mechanism of the class described comprising a fixed cradle, a bearing element located therein, a crank shaft passing thru and rotatably supported by said bearing element, said bearing element comprising a bushing and an oil directing cage positioned thereabout and a rotor member supporting the said bushing and interlocking with said cage, a series of spaced apart pockets carried on the periphery of the said bearing element, spaced apart bridge portions carried within said cradle, providing an oil receiving and pressure zone, tooth like portions carried on the periphery of said rotor member and an inlet opening connecting supply oil with the rotor and means for rotating the same, whereby oil in the said pockets will be urged upwardly and into the said pressure zone, baffle means carried by the cradle that 50 act with the rotor in such a manner as to cause the said oil within the aforesaid zone to be compressed and providing a vacuum 55 wherein supply oil is urged within the receiving zone, outlets carried by the cage member that automatically open and close at predetermined points in their rotation thereby admitting compressed oil into the bore of the bushing, causing the same to be retained, and then discharging the used lubricant upon each rotation of the bearing element, and drain means spaced apart from the bore of the bushing and positioned parallel thereto, that 60 direct the said discharged oil outwardly.
5. An oil film adjusting device as described the combination with a fixed cradle and a rotor element positioned therein, an expandible and contractible bushing element rotatably positioned within the said rotor and a crankshaft passing thru, said device consists of the said rotor element being formed in longitudinal sections, the one section having a reduced inner end portion thread engaging with the converse reduced inner end portion of its companion section, and the twain having an inner periphery whose form registers with the oppositely disposed angles of the said bushing which the rotor supports, manually operated means provided, the action of which causes the said thread engaging rotor unit to slightly lengthen, and by reason of its registering contact with the bushing the film of lubricant within the bore of the bushing is thereby reduced, and by a reverse turn of the unlocked section of the rotor, will cause the said film to increase in gauge, and means provided to lock the rotor element and the bushing mechanism as an operative unit after its adjustment.
6. An oil scavenger device as described the combination with a fixed cradle and a bearing element located therein, a crank shaft passing thru and rotatably supported by the said bearing element which element has a series of longitudinal spaced apart pockets on its periphery, an inlet opening connecting with said pockets, and means for rotating the bearing element, said scavenger device con-

- sisting of a suitable roller, which roller is adjustably carried within a slot positioned within the said cradle and the said slot being aligned directly adjacent to the ends of the 5 said pockets carried on the periphery of said bearing element, means to intermittently bypass pressure oil to the outer surface of said roller for maintaining the roller in traction engagement with the contour of the pocket 10 walls and auxiliary means carried within the outer portion of said slot that also coat with the roll, thereby causing the oil within the rotating pockets to be forced therefrom, a 15 source of oil pressure, and simultaneously a suitable vacuum, wherein supply oil is urged to enter thru said inlet and then upwardly, as shown and described.
7. In an oil passage device, the combination with a main power driven bearing, a source of 20 oil pressure, said bearing supporting a crank shaft and a connecting rod bearing mounted upon the shaft crank, which bearings are spaced apart by an arm of the said crank: said device consisting of means carried within 25 the adjacent ends of said bearings, which means revolvably interengage with suitable means positioned upon the opposite faces of said arm, there being a passage way carried by the arm which directly connects suitable 30 passages carried by the adjacent ends of the

bearings, whereby service oil is permitted to flow from the main bearing and into the other, irrespective of their rotative positions, one with the other.

8. In an oil passage device, the combination 35 with a plurality of main power driven bearings, a source of oil pressure, said bearings supporting a crank shaft and a plurality of connecting rod bearings mounted upon the said shaft cranks, and the main bearings 40 spaced apart from said rod bearings by the crank arms, said device consisting of suitable means carried within the adjacent ends of the several pairs of aligned bearings, which means revolvably interengage with concentric 45 ledges carried upon the opposite faces of the said crank arms; there being passage ways carried by the arms, said ways being positioned within the arm portions at an angle to their radius of action and directly connected 50 with said means, within the bearing ends, and suitable means carried by the intermediate crank arms, by which the rod bearings are channel connected in pairs, whereby oil is urged to flow continuously into and thru the 55 complete bearing assemblage beyond the contour of the shaft and irrespective of their rotative positions, relative to each other.

FRANCIS E. BUXTON.
